UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,262,752.

Specification of Letters Patent. Patented Apr. 16, 1918.

Application filed April 26, 1917. Serial No. 164,651.

To all whom it may concern:

Be it known that I, HENRY P. CLAUSEN, a citizen of the United States, residing at Mount Vernon, in the county of Westchester 5 and State of New York, have invented certain new and useful Improvements in Telephone Systems, of which the following is a full, clear, concise, and exact description.

This invention relates to telephone systems, and has for its object the provision of a cheaply produced, efficient means through which a number of subscribers may inter-communicate.

The essential feature of this invention is 15 the means of establishing connection between subscribers, by the use of relays which are only energized while the connection is being established.

The circuit arrangements are somewhat 20 similar to those described in the patent to Clement, 939,186. Here, as there, two relays are employed to complete a connection between a so-called "tens relay" and a so-called "units relay". The units relay ex- 25 tends the calling line to one of ten trunks which are extended by the tens relay to ten lines of a certain group. There is one im- 30 portant difference between the two schemes, however, and that is the number of tens relays that are employed.

A feature of the present invention, then, 35 is the use of one less tens relay than the number of groups of lines. According to this feature the telephone numbers whose 40 digit should be zero may be employed in the ordinary manner in which numbers are expressed. In other words, those telephones which belong in the zero group may be called through the actuation of a units re- 45 lay only, the actuation of a tens relay being unnecessary.

According to the first-mentioned feature 50 a relay when energized has its armature mechanically locked in the actuated position. The locked armature may then be released through special releasing means, or it may be left in the actuated position until a new call is made. In the latter case another relay, upon being energized, will release the 55 first locked armature and have its armature locked after the manner in which keys are locked, as described in the patent to Ham, No. 634,575.

Through such an arrangement no current 55 is allowed to flow through the connecting

relays during conversation and the drain upon the batteries is extremely light, no expensive power plant is necessary, it being possible to utilize inexpensive dry batteries for the operation of this system. 60

It is thought that the invention will best be understood from the following detailed description, reference being had to the accompanying drawing, in which the portion to the left of the left-hand broken line represents the apparatus and connections at a substation; the portion between the two broken lines represents the apparatus and connections at a connecting box; and the portion to the right of the right-hand broken line represents the main cable with an indicated called substation connected to one of the lines. 65

For the sake of simplicity, the system has 70 been shown as a single conductor system with a common return, the common return being indicated as a ground connection, although it should be understood that a single conductor may be used instead of a ground connection. 75

It should further be understood that this 80 arrangement is not limited to a single conductor system since it might as well be a two conductor metallic circuit system without changing the spirit of the invention. 85

The calling substation S is provided with a transmitter T, a receiver R, an induction coil I, a condenser C, a switchhook H, and a call bell B. There are provided a number of buttons T¹, T² and T³, which control the 90 tens relays. There are also provided ten buttons U⁰ to U⁹ inclusive, which control the units relays. In addition, there is a button S¹⁷, which controls, as shown, the first tens relay and the eighth units relay. 95 The button A is known as the answering button, and is provided to restore the apparatus to normal condition, in which a call to this station may be answered. A button K, connected within the substation circuits, 100 itself is used for ringing a called line after the connection has been set up by the pressure of the proper tens and units buttons.

The connecting box contains a number of 105 tens relays, three being shown, Nos. 1, 2 and 3. In addition there are ten units relays, Nos. 10 to 19 inclusive. The armatures of the tens relays are controlled through a locking plate P¹ in a manner similar to that described in connection with the key in the 110

before-mentioned patent to Ham. The cams 5, 6 and 7, attached to the armatures of the relays 1, 2 and 3 respectively, coöperate with the plate P^1 in such a manner that upon the 5 energization of any one of these relays it will be mechanically locked in the energized position, and held in that position until the plate P^1 is moved downwardly under the influence of the magnet 8, controlled by the 10 button A. Another one of the tens relays, upon being energized, will release the first locked relay and itself become locked. The same arrangement is provided for the ten units relays, the plate P^2 controlling these 15 relays in a similar manner.

The main cable consists of what might be called the multiple of this system, that is, a single conductor for each one of the substations with the necessary conductors for supplying battery current, etc. It is intended 20 that this main cable shall be run through a building where such a system is installed to a convenient point where the connecting box may be located, and from which connecting 25 box a cable carrying a much smaller number of conductors be run to the substation itself.

The battery supply may be as indicated in the portion designated the main cable, and consists of a battery of low potential connected 30 in series with a battery of a higher potential, with conductors leading from either end through the main cable to the connecting box. The battery of higher potential is extended to the connecting relays and 35 forms the source of current through which these relays are operated. It also is extended to the lower contact of the button K, and is thereby used as a source of current through which the substations may be rung.

40 The battery of low potential is extended through the main cable to the connecting box, where it is led through an impedance coil 9 to the left-hand armature and contact of relay 10, left-hand armature and contact of relay 11, and so on to the left-hand armature and contact of relay 19, thence over the conductor 20 to the switch-hook of the subscriber's set.

When each of the relays 10 to 19 inclusive 45 is deenergized, battery is supplied over the circuit just traced to the telephone set S, and when the receiver at that point is removed, current flows over this circuit through the primary of the induction coil I, the transmitter T, to the common return wire. When the receiver is on the hook, a small amount of current flows through the 55 normal contact of the switchhook, the upper contact of the button K, the polarized bell B, to the common return wire. The resistance 60 of the circuit through the polarized bell B, however, is so great that the current flow is extremely small and may be considered negligible. Moreover, the polarized bell B is connected in such a way that the

current flowing in the direction as at present has no effect. However, when another substation has established a connection to substation S, and when the button K at this other calling substation is depressed, a circuit is established from the battery of higher potential, lower contact of key K, at the calling substation, switchhook H at the calling substation, line wire corresponding to conductor 20, through the relay contacts associated with the calling substation to the multiple wire at substation S, conductor 20, lower contact of switchboard H, upper contact of key K, polarized bell B, to the common return wire. In this manner the current flowing through the bell B is reversed and increased, and the bell rings. The construction and operation of such polarized bells, and the manner of their use is so well known that no further description is considered necessary.

It will be noted that the substation S is extended through the conductor 20 in multiple to the right-hand contacts of the units relays 10 to 19 inclusive, and thence to connection with one of the conductors in the main cable, the conductor shown in this case being in the third tens group and the seventh conductor in that group. The designation of substation S would therefore be 26.

A called substation is shown connected to the ninth conductor in the zero group, the designation of such a telephone being 8.

The establishment of a connection between telephone No. 26 and telephone No. 8 will now be described. The subscriber at substation S presses the button U^8 and establishes thereby a connection from the common conductor ground, the contact of button U^8 , winding of relay 18, to the conductor 21, and thence through the main cable to the free pole of the battery of higher potential, and thence to the common return. The relay 18 attracts its armatures and through the agency of plate P^2 locks 110 them in their actuated positions, where they remain when pressure is removed from the conductor U^8 .

Since the designation of the called telephone is 8, no tens relay need be energized, since the connection is now established from the substation S through the conductor 20, the right-hand contact and armature of relay 18, the second from the left armature and normal contact of relay 3, the second from the left armature and normal contact of relay 2, the second from the left armature and normal contact of relay 1, to the conductor 22 leading to the substation S^1 .

The subscriber at substation S now depresses the button K, whereupon a circuit is established from the free pole of battery of higher potential to the lower contact of the button K, the conductor 20, and thence

over the circuit traced to the substation S^1 , where it travels through the lower contact of the switchhook at that point, the polarized bell, to the common conductor. The 5 polarized bell is actuated through the flow of current in this circuit.

The subscriber at substation S^1 , in answering the summons of his bell, depresses his key A, which energizes a relay similar in 10 function to relay 8, and releases any tens or units relay which may be in actuated position at that point. Talking current is supplied from the free pole of low potential battery, and the impedance coil similar to 15 9 which is connected in the circuit of the substation S^1 .

At the conclusion of the conversation the subscriber at substation S may simply replace his receiver on its hook or he may, if 20 he so desires, press the button A and restore any tens or units relay which is in the actuated position.

For the convenience of certain subscribers, buttons such as S^{17} may be provided. 25 These buttons are useful in calling, by the pressure of one button, a certain desired party. Suppose, for instance, that the subscriber at substation S were the superintendent of a factory, and that the party with 30 whom he is in most direct contact is a party whose telephone number is 17. He may then have a button provided to call this substation without going through the usual operation of pressing a tens and a units button. 35 It is apparent that the pressure of button S^{17} will energize the units relay 17, and the tens relay No. 1, so that a circuit will be established from the substation S, over the conductor 20, through the contact and right-hand armature of relay 17, the third from the left armature and normal contact of relay 3, the third from the left armature and normal contact of relay 2, the third from the left armature and alternate contact of 40 relay 1, to the eighth conductor in the second group in the main cable, such conductor leading to the substation 17. The operation of ringing the subscriber is the same as described in the previous case.

45 It should be noted that if such a system as herein described is to be supplied with service from a central telephone exchange, the trunks of such an exchange may be connected to any one of the multiple wires shown in the main cable, and when connection is made to this trunk, that talking current is supplied from the trunk and not from the local impedance coil, since one of the relays 10 to 19 must be energized.

50 Since the means for receiving calls from the central exchange forms no part of the present invention, and circuits for such use are well-known, they will not be described in the present instance.

55 It should be noted especially, that through

the connections of the trunks leading from the units relays to the tens relays, and through the armatures and contacts of the tens relays, the arrangement is such that these trunks are connected, when no tens 70 relay is energized, directly to the zero group of lines, so that the energization of a units relay only is necessary when a one-digit number is to be called.

What is claimed is:

1. In a telephone system, telephone lines, relays for establishing connections between said lines, said relays being energized only while said connections are being established, and mechanical means common to said relays for locking said relays in their energized positions. 75

2. In a telephone system, telephone lines, relays for establishing connections between said lines, said relays being arranged to be 80 energized only while said connections are being established, mechanical means common to said relays for locking said relays in their energized positions, and means for restoring said relays to their normal positions. 85

3. In a telephone system, telephone substations, relays for establishing connections between said substations, means located at said substations for operating said relays, and mechanical means common to said relays for holding said relays in their energized positions. 90 95

4. In a telephone system, telephone substations, relays for establishing connections between said substations, means located at 100 said substations for operating said relays, mechanical means common to said relays for holding said relays in their energized positions, and automatic means for restoring said relays to their normal positions. 105

5. In a telephone system, telephone substations, relays for establishing connections between said substations, means located at 110 said substations for operating said relays, mechanical means common to said relays for holding said relays in their energized positions, automatic means for restoring said relays to their normal positions, and means located at said substations for restoring said relays to their normal positions. 115

6. In a telephone system, telephone lines arranged in groups, a group of connecting circuits, a group of relays for extending said lines to said connecting circuits, a group of relays for extending said connecting circuits to said lines, means for operating said relays, and means common to each said group of relays for mechanically holding said operated relays in their actuated positions. 120 125

7. In a telephone system, telephone lines arranged in groups, a group of connecting circuits, a set of relays for extending said lines to said connecting circuits, a set of relays for extending said connecting circuits 130

to said lines, means for operating said relays, means common to each said set of relays for mechanically holding said operating relays in their actuated positions, and 5 automatic means for restoring said relays to their normal positions.

8. In a telephone system, a plurality of groups of telephone lines, a group of connecting circuits for interconnecting said 10 telephone lines, a group of relays equal in number to said connecting circuits for extending said lines to said connecting circuits, a group of relays one less in number than said groups of lines for extending said 15 connecting circuits to said lines, means for operating said relays, and mechanical means for holding said relays in their actuated positions.

9. In a telephone system, a plurality of 20 groups of telephone lines, a group of connecting circuits for interconnecting said telephone lines, a group of relays equal in number to said connecting circuits for extending said lines to said connecting circuits, a group of relays one less in number than said groups of lines for extending said 25 connecting circuits to said lines, means for operating said relays, mechanical means for holding said relays in their actuated positions, and means for restoring said relays to their normal positions.

10. In a telephone system, groups of telephone lines, a group of connecting circuits normally extended between said groups of 30 lines, a set of relays equal in number to said connecting circuits for extending said lines to said connecting circuits, and a set of relays one less in number than said groups of lines for switching said connecting circuits 35 from association with the group of lines to which they are normally extended into operation with others of said groups of lines.

11. In a telephone system, groups of telephone lines, a group of connecting circuits normally extended between said groups of 40 lines, a set of relays equal in number to said connecting circuits for extending said lines to said connecting circuits, a set of relays one less in number than said groups of lines

for switching said connecting circuits from 50 the group of lines to which they are normally extended to others of said groups of lines, means for operating said relays, and means for mechanically holding said relays in their actuated positions. 55

12. In a telephone system, groups of telephone lines, a group of connecting circuits normally extended between said groups of lines, a set of relays equal in number to said connecting circuits for extending said lines 60 to said connecting circuits, a set of relays one less in number than said groups of lines for switching said connecting circuits from the group of lines to which they are normally extended to others of said groups of 65 lines, means for operating said relays, means for mechanically holding said relays in their actuated positions, and means for restoring said relays to their normal positions.

13. In a telephone system, telephone lines, 70 relays for establishing connections between said lines, said relays being energized only while said connections are being established, mechanical means for locking said relays in their energized positions, said mechanical 75 means being responsive to the last relay to be actuated to lock only said last actuated relay.

14. In a telephone system, groups of telephone lines, a group of connecting circuits 80 for interconnecting said telephone lines, a group of relays equal in number to said connecting circuits for extending said lines to said connecting circuits, a group of relays one less in number than said groups of telephone lines for extending said connecting 85 circuits to said lines, means for operating said relays, mechanical means individual to each said group of relays for holding said relays in their actuated positions, said mechanical means being responsive to the last relay of the group to be actuated to hold only said last actuated relay in its actuated position.

In witness whereof, I hereunto subscribe 90 my name this 25th day of April, A. D. 1917.

HENRY P. CLAUSEN.
